CLAIM

The ornamental design for an automatic pet feeder, as shown and described.

DESCRIPTION

FIG. 1 is a front and top perspective view of an automatic pet feeder, showing an automatic pet feeder body connected with a tray by a connector;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded view thereof;

FIG. 10 is a perspective view thereof, showing the automatic pet feeder installed on a pet cage;

FIG. 11 is a front and top perspective view showing the automatic pet feeder body only installed with the tray;

FIG. 12 is a front and bottom perspective view thereof; and,

FIG. 13 is a rear and top perspective view thereof.

The broken lines in the figures illustrate portions of the article that form no part of the claimed design.
